UNITED STATES PATENT OFFICE.

SELDEN H. HALL, OF POUGHKEEPSIE, NEW YORK, ASSIGNOR TO THE DE LAVAL SEPARATOR COMPANY, OF NEW YORK, N. Y., A CORPORATION OF NEW JERSEY.

SEALING DISCHARGE-PASSAGES OF CENTRIFUGALIZING-MACHINES AND THE LIKE.

1,100,872.

Specification of Letters Patent. Patented June 23, 1914.

Application filed March 26, 1913. Serial No. 756,835.

To all whom it may concern:

Be it known that I, SELDEN H. HALL, a citizen of the United States, residing at Poughkeepsie, county of Dutchess, State of New York, and whose post-office address is c/o De Laval Separator Company, Poughkeepsie, New York, have invented certain new and useful Improvements in Sealing Discharge-Passages of Centrifugalizing-Machines and the like; and I do hereby declare the following to be a full, clear, and exact description of the invention, such as will enable others skilled in the art to which it appertains to make and use the same.

In nearly all forms of continuous centrifugalizing machines, the treated fluid is either discharged over a ring in a thin sheet or escapes through a hole in a small stream; and in either case, it soon breaks into a fine spray which flies through the air until it strikes the wall of the receiving vessel. In many cases, this passage through the air in a finely divided state is very deleterious. With some materials volatile parts are evaporated. With others, there is considerable oxidation; and with others there is an entrainment of air which makes a froth or foam that causes a serious inconvenience, if not an absolute loss, in subsequent operations. This is particularly so with centrifugal separators and clarifiers for milk, which, with the ordinary designs of discharge and receiving apparatus, naturally forms a froth that causes much trouble in bottling machines and in some forms of pasteurizing apparatus, and which is rich in butter fat so that if skimmed off it is a positive loss from the treated milk.

The present invention relates to an improved method and apparatus for discharging the treated fluid, primarily designed to overcome these disadvantages in the operation of centrifugalizing machines, but quite generally applicable to sealing the discharge from one receptacle to another in any case where a stuffing box or like permanent mechanical seal cannot be used or is for any reason undesirable.

In accordance with the invention, the fluid passing from one receptacle to the other is sealed, against admission of or contact with the air or other surrounding atmosphere, by a sealing body of liquid through which the fluid is discharged; and suitable expedients are adopted for the purpose of pre-

venting the draining away of the sealing liquid by the discharged fluid passing therethrough. In the specific application of the invention to centrifugalizing machines, the rotating bowl carries a plurality of annular plates which revolve with the bowl and are so spaced apart as to form between them a narrow annular discharge throat, the mouth of which stands opposite and in close proximity to the receiving mouth of a like annular throat on a stationary receiving vessel. The fluid passes out of the revolving mouth of the bowl into the stationary mouth of the receiving vessel at such high velocity that it tends to draw air into the passing fluid and thus into the receiving chamber, thereby giving rise to the objectionable effects above set forth. For the purpose of avoiding this drawing in of the surrounding air, the mouth is surrounded by an annular chamber or receptacle for a body of sealing liquid through which the fluid is discharged. In order to prevent the drawing away of the sealing liquid by the discharged fluid passing therethrough, there may be employed, in accordance with the present invention, a pressure directed against the draining effect and sufficient to maintain a sealing body of liquid in the surrounding annular chamber or receptacle. The desired pressure may be attained either by reducing the pressure on that surface of the sealing liquid which is exposed to the air, or by applying to some other portion of the liquid seal a suitable back pressure; or by a combination of these two expedients. The most simple and the preferred method of accomplishing the desired result is to establish a pressure above atmospheric in the receiving vessel, by means of a controlled outlet from that vessel; and I have found that by properly adjusting the pressure in the receiving vessel, a portion of the liquid passing from the bowl into the receiving vessel may be forced back into the annular chamber or receptacle surrounding the mouths and may thus form a liquid seal, which will effectually prevent the entrance of air, and yet, if the back pressure is not excessive, will cause no substantial leakage of the liquid.

Inasmuch as the annular chamber or receptacle for the liquid seal is horizontally arranged, there will be a tendency, due to the action of gravity, for the liquid constituting the seal to flow away from the region

in which it should be maintained into the lower portion of the annular chamber or receptacle and I have found that this tendency may effectively be overcome by making proper use of the centrifugal force which is present. In the arrangement shown in the accompanying drawings, the surrounding annular chamber or receptacle for the liquid seal is formed in the stationary receiving vessel, so that the discharge mouth of the bowl is at the greatest diameter of this surrounding chamber. In this case, the liquid constituting the seal, which lies between the rotating throat of the bowl and the stationary walls of the surrounding chamber, will be urged by the centrifugal force toward the region of sealing and the leakage effect of gravity will to that extent be overcome. Further precautions against leakage may be taken by providing a series of annular shelves below the seal chamber. On the shelf next below the seal chamber the tendency of the centrifugal force would be to increase the leakage, and on the shelf below that the tendency would be to decrease the leakage, and so on. Under these circumstances, it is possible to take advantage of the centrifugal force on the several shelves to oppose the force of gravity, by giving to the surfaces of the shelves such a configuration that the sealing liquid will be accelerated, in its rotary movement, in those intershelf spaces in which the leakage tendency of gravity is to draw the liquid toward the axis of revolution, and will be retarded in its rotary movement in those intershelf spaces in which the leakage tendency of gravity is to draw the liquid away from the axis of rotation.

In the accompanying drawings, Figure 1 shows in section and partly in elevation, the upper body portion and neck of a rotating centrifugalizing bowl, which may be of any approved form, together with the inclosing casing, a superposed filling receptacle, and a surrounding receiving vessel; Fig. 2 is a plan view from beneath of the cover plate F; and Fig. 3 is a section showing in plan one of the annular shelves.

The bowl A has a contracted neck, as is usual in milk separating centrifugals, and on the outside of the neck is formed a shelf B for the reception of a packing ring C on which rests a member D forming one of a pair of annular rings, the other one being the member U. These members are forced down on the packing ring by spacing ribs E (see Fig. 2) on the under side of an annular cover plate F having a screw threaded hub which engages with corresponding screw threads on the center tube G of the bowl. On the upper end of the casing H is screwed an annular member I constituting a portion of the receiving vessel and to guard against leakage at this joint, a packing ring J is in-

terposed, as shown. The member I carries an annular shelf K which is interposed between the shelves on the members D and U. Resting upon the outer rim of the member I and held thereto by the clamping ring L is the filling receptacle M, the lower peripheral portion of which is shaped to complete the configuration of the annular receiving chamber; and it will be understood that this chamber, which is here shown of annular form, may be of a volute or any form that best suits the particular case. Leakage from the receiving chamber at the joint between the member I and the rim of the vessel M is guarded against by the interposition of the packing ring N. The member I and the bottom of the vessel M are shaped, as shown, to form a narrow annular mouth and throat for the receiving vessel, which is directly opposite and in close proximity to the discharge mouth of the bowl. The filling vessel M has a discharge spout O entering the central tube of the centrifugal. For the purpose of controlling the pressure within the receiving vessel, the discharge conduit P is provided with a controlling valve R as shown. It will be observed that when this construction is adopted the narrow annular discharge throat of the centrifugal extends within an annular chamber, between the bottom of the vessel M and the stationary shelf K, in which it revolves with small clearance, and beneath the shelf K a tortuous passage is formed by the shelf on the member D and the inwardly projecting shelf S on the outer casing of the centrifugal.

The operation of the device is as follows: The liquid to be treated is supplied to the feed vessel M and from there passes through tube O into the bowl A. After treatment, the liquid rises up in a thin layer inside the neck of the centrifugal and entering the narrow throat between the cover plate F and the upper shelf of the member U it is discharged at great velocity into the mouth and through the throat of the annular receiving vessel. The fluid thus passing into the receiving vessel tends to draw in the surrounding air, but by manipulating the discharge valve R in the discharge conduit of the receiving vessel, or by discharging against a hydraulic head, or by other approved means, a pressure is created in the receiving vessel which has the effect to cause part of the liquid to flow back into the space between the throat of the bowl and the walls of the annular chamber in which that throat revolves. An increase of the back pressure will force the liquid back over the upper surface of the cover plate F and also back over the upper surface of the shelf K and through the underlying tortuous passages. The passage of liquid back over the upper surface of the plate F would do no harm because it would run back into the bowl; and leakage

by the outflow of the liquid over the shelf K may be prevented by making use of the centrifugal force as above described. To this end the under surface of the throat of the 6 bowl and the upper surface of the shelf K should have such a configuration as to accelerate the rotary movement of the liquid in the space between them. If the centrifugal force thus developed is not sufficient to 10 overcome the back pressure and the effect of the weight of the liquid, some liquid will pass around the inner edge of the shelf K into the space between the lower surface of that shelf and the upper surface of the shelf 15 on the member D; and the liquid may even pass around the outer end of that shelf into the space between the under surface thereof and the upper surface of the stationary shelf S. It will be observed that in the first 20 of these spaces the centrifugal force is opposed to the force of gravity, in the second, it assists the gravity, and in the third it is opposed. The total opposing effect of the centrifugal force in these several spaces may 25 be increased by so constructing the shelves that the rotary movement of the liquid is accelerated in the first and third intershelf space, and is retarded in the intermediate intershelf space. To this end the configuration 30 of the surfaces of the shelves should be such that the liquid tends to move with the rotating shelf and to slip over the stationary shelf in the upper space and the lower space, while it tends to slip over the 35 moving shelf and remain with the fixed shelf in the intermediate space. This effect may be accomplished by providing projections such as the radial ribs T shown in Fig. 3, or ribs of any approved form, on the appropriate surfaces, that is, on the rotating surfaces in those spaces where the liquid is to be accelerated and on the stationary surfaces in those spaces where the liquid is to be retarded. In practice, I have found that it is 40 sufficient to make the surfaces of the stationary shelves quite smooth in the upper and lower spaces and to provide the projections on the under surface of the shelf K for the purpose of retarding the liquid in the intermediate space; but obviously further application may be made of these projections if desired, or the surfaces may be otherwise shaped to attain the described effect. Obviously, if for any reason it is desirable to use 45 a high pressure in the receiving chamber, the number of shelves in the seal may be increased to the extent needed to prevent leakage.

What I claim is:—

- 60 1. A centrifugalizing machine having a rotary vessel with an annular discharge mouth, a stationary receiving vessel having an annular receiving mouth confronting the annular discharge mouth of the rotary vessel, and a receptacle for holding a liquid

70 seal at the region of passage of the discharge fluid from the discharge mouth to the receiving mouth, the receptacle being so arranged with relation to the mouths that the discharge fluid passes through the liquid 75 constituting the seal; substantially as described.

2. A centrifugalizing machine having a rotary vessel having an annular discharge mouth, a stationary receiving vessel having an annular receiving mouth confronting the annular discharge mouth of the rotary vessel, a receptacle for holding a liquid seal 80 at the region of passage of the discharge fluid from the discharge mouth of the receiving mouth, the receptacle being so arranged with relation to the mouths that the discharge fluid passes through the liquid 85 constituting the seal, and means for maintaining a difference of pressure on two surfaces of the sealing liquid in the receptacle sufficient to prevent the emptying of the receptacle by the discharge fluid passing through the liquid therein; substantially as described.

90 3. A centrifugalizing machine having a rotary vessel with an annular discharge mouth, a stationary receiving vessel having an annular receiving mouth confronting the annular discharge mouth of the rotary vessel, a receptacle for holding a liquid seal 95 at the region of passage of the discharge fluid from the discharge mouth to the receiving mouth, the receptacle being so arranged with relation to the mouths that the discharge fluid passes through the liquid 100 constituting the seal, and means for maintaining a sufficient pressure in the receiving vessel to prevent the emptying of the receptacle by the discharge fluid passing 105 through the liquid therein; substantially as described.

4. A centrifugalizing machine having a rotary vessel with an annular discharge mouth, a stationary receiving vessel having an annular receiving mouth confronting the annular discharge mouth of the rotary vessel, a receptacle for holding a liquid seal 110 at the region of passage of the discharge fluid from the discharge mouth to the receiving mouth, the receptacle being so arranged with relation to the mouths that the discharge fluid passes through the liquid 115 constituting the seal, a discharge conduit from the receiving vessel, and a valve in the discharge conduit adapted to restrict the flow therethrough and thereby maintain in the receiving vessel sufficient pressure to prevent the emptying of the seal receptacle by the discharge fluid passing through the liquid 120 therein; substantially as described.

5. A centrifugalizing machine having a narrow annular discharge mouth, a receiving vessel having a narrow annular receiving mouth in close proximity to the dis- 130

charge mouth of the rotary vessel, and annular overlapping shelves supported alternately from the receiving vessel and from the rotary vessel and constituting a receptacle for a liquid seal through which the discharge takes place; substantially as described.

6. A centrifugalizing machine having a narrow annular discharge mouth, a receiving vessel having a narrow annular receiving mouth in close proximity to the discharge mouth of the rotary vessel, and annular overlapping shelves supported alternately from the receiving vessel and from the rotary vessel and constituting a receptacle for a liquid seal through which the discharge takes place, a discharge conduit leading from the receiving vessel, and a controlling valve in said conduit adapted to 15 maintain in the receiving vessel sufficient pressure to prevent the draining away of the liquid seal by the discharge fluid passing therethrough; substantially as described.

7. A centrifugalizing machine having a rotary vessel with an inclosing casing, annular shelves secured to the upper end of the rotary vessel, a cover plate above the top shelf and spaced apart therefrom to form a narrow annular discharge mouth, a casing for the rotary receptacle, a member constituting a portion of a receiving vessel supported on said casing and having an annular shelf lying between the annular shelves on the rotary vessel, and a filling vessel supported on said member and completing the contour of the receiving vessel, the said member and the said filling vessel being shaped to afford a narrow annular receiving mouth confronting the mouth of the rotary vessel; substantially as described. 25 30 35

In testimony whereof I affix my signature, in presence of two witnesses.
